UNITED STATES PATENT OFFICE.

JOSEPH GANNON, OF WALTON, NEW YORK, ASSIGNOR TO STEINFELD BROS., OF NEW YORK, N. Y., A FIRM COMPOSED OF SAMUEL STEINFELD AND LEO STEINFELD.

BABY-WALKER.

1,256,548.

Specification of Letters Patent. Patented Feb. 19, 1918.

Application filed February 25, 1914. Serial No. 820,891.

To all whom it may concern:

Be it known that I, JOSEPH GANNON, a citizen of the United States of America, and resident of Walton, in the county of 5 Delaware and State of New York, have invented certain new and useful Improvements in Baby-Walkers, of which the following is a specification.

This invention relates to the article of domestic furniture generally termed a "baby-walker"; which, it may be explained, has generally consisted of a base-ring of comparatively great diameter, means carried thereby to permit of travels thereof over the 10 floor without material friction, and a structure supported above the base-ring which usually included a seat and circular breast-rail arranged at such a height above the center of the base-ring that the suspended feet 15 of the infant could engage and push against the floor to propel the structure, the circular breast-rail being of sufficiently less diameter than the base-ring to protect the occupant of the seat from accidental injury. 20

25 The cardinal object of the present invention is to provide a structure of the above type, but one characterized by many novel advantages, the more important of which 30 are to provide a construction that is collapsible when desired so that the collapsed article will be very compact; to provide a rigid, dependable and inexpensive arrangement of the parts, and to provide a safe locking means for maintaining as long as 35 desired the expanded condition of the device.

Other objects and aims of the invention, more or less broad than those stated above, together with the advantages inherent, will 40 be in part obvious and in part specifically referred to in the course of the following description of the elements, combinations, arrangements of parts, and applications of principles constituting the invention; and 45 the scope of protection contemplated will appear from the claims.

In the accompanying drawings, there is disclosed an embodiment of the present invention as at present preferred; and in these 50 drawings, which are to be taken as a part of this specification,

Figure 1 is a top plan view of said embodiment;

Fig. 2 is a vertical sectional view, taken 55 on the line 2-2 of Fig. 1;

Fig. 3 is a detail view, on an enlarged scale, showing in what may be termed "front elevation" certain of the parts disclosed in Figs. 1 and 2; and

Fig. 4 is a similar view, but partly in section, showing said parts in what may be termed "side elevation," illustrated in full lines in expanded condition and in broken lines in collapsed condition.

The present embodiment, as shown, includes a base-ring 5 of a usual type adapted to have built up in connection therewith the general structure.

Said base-ring carries on its underside a suitable plurality of preferably swiveled 70 rollers 6 (but two of which are illustrated), and on its upper surface three T-brackets 7, as indicated. Pivotedly mounted upon each of said brackets is a built-up strut including a pair of bars 8; said strut including 75 also a single bar 9 which may when desired, and as hereinafter explained, serve to prolong the strut-structure as shown in full lines in the drawings.

The upper terminal portion of each bar 80 9 is pivotally mounted as shown at 10 upon one of the T-brackets 11. Each T-bracket 11 is dependent from the underside of the circular breast-rail 12, and each carries a stop-pin 13 adapted to coöperate with its adjacent bar 9 as illustrated. The functions of 85 these stop-pins will be understood, if it be noted at this point that the weight of the infant is suspended as hereinafter described from the breast-rail 12; and the reason for 90 preferably arranging the stop-pins alongside the outer edge rather than adjacent the inner edge of each bar 9 (see Fig. 3) will be understood too, if it is also noted at this point that upon the present structure collapsing to the broken-line condition shown 95 in Fig. 4, each bar 9, as indicated, will be enabled to clear its associated stop-pin (see Fig. 4).

Suitably suspended from the breast-rail 100 12 are a plurality (in the present instance, four) of retractile springs 14; from each of which, in turn, is suspended one of the seat-supporting straps 15. The seat itself, which may be given the reference numeral 16, is 105 preferably shaped as illustrated, and also preferably carries a post or the like similar to the post 17. A trav 18 is disclosed as being carried by the breast-rail 12.

Let us assume at this point, still deferring 110

temporarily a description of the means provided for permitting of a collapsing of the structure, that the device is expanded, that is, in the condition illustrated say in Figs. 1 5 and 2, so that the manner of operation thereof may now be explained. The infant is placed upon the seat 16 so that he faces the tray 18, his arms are free above the breast-rail 12, his legs extend downwardly through 10 the spaces 16' and straddle the post 17, and his feet are within effective reach of the floor. He is thus supported in such a way that he may exercise his leg muscles to propel himself and actually take definite steps, 15 and even maintain standing postures at brief intervals, without danger of losing his balance and falling and also without any possibility of setting up the usual deformities which follow the undue strains of early 20 walking. The base-ring projects sufficiently to come into contact with the lower portions of tables and the like in such a way that the child's head and other portions of his body are adequately safeguarded.

25 Now to take up a description of the collapsible feature of the invention; and in connection with which, allusions to the structure provided will in the main refer to Figs. 3 and 4.

30 In each case, bars 8 are spaced apart (Fig. 3) by means of the five transverse rivet-pins 19, 20, 21, 22 and 23, each of which pins also serves an additional function, as will be indicated. Pin 19, slidably and pivotally links together bars 8 and bar 9, this pin passing through the slot 24 formed in bar 9. Pin 20 serves to coöperate as hereinafter described, and as shown in full lines in Fig. 4, with the notched terminus of bar 9. Upon pin 21 is pivotally hung the latch-member 25, and coiled about pins 22 and 23 as disclosed, is a leaf or wire-spring 26 so arranged as to be effective always to urge latch-member 25 from its broken-line 45 location 25' to the full-line location thereof shown in Fig. 4. Bar 9 is provided in its outside edge with a V-notch 27, adapted at certain times to coöperate as disclosed with the toothed end of the latch-member, the 50 latch-member being also provided with an operating portion 28.

A preferable manner of collapsing the structure, assuming that the means described in the preceding paragraph at present, is 55 substantially as follows: It is preliminarily to be understood, of course, that the parts of each strut are disposed as shown in full-lines in Fig. 4. Thus disposed there is present a rigid and sturdy frame-work adequate 60 to maintain the integrity of the structure until sufficient pressure is applied to the operating portion of the latch member 25 to overcome the normal tension of the spring 26, the tension of which preferably is made 65 great enough to withstand any accidental re-

leasing movement of the latch-member, whether due to a contact with articles of furniture or the like or to any tampering therewith by the occupant of the "walker." When once the toothed end of each latch-member is engaged with the V-notch carried by the adjacent bar 9, the bars 8 cannot slide along their adjacent bars 9 in the direction indicated by the arrow of Fig. 4, and thus each of the pins 20 is insured 70 against disengagement from the coöperating terminus of the adjacent bar 9; the stop-pins 13 serving, as described hereinabove, to prevent any considerable movement of breast-rail 12 relatively of base-ring 5. 75

To collapse the structure, sufficient pressure is applied to the operating portion of each latch-member 25 to lift the toothed end thereof free of its adjacent V-notch in bar 9. Each of the bars 9 is then moved relatively of the thereto-linked bars 8, and in the direction of the arrow (Fig. 4), until the tip of the tooth of each latch-member 25 rides against the outer edge of its adjacent bar 9. Slots 24 permit of the just-described operations, and each of the slots is preferably so designed that it will constitute a stop for its pin 19 when the free end of its bar 9 is able to be swung in a clockwise direction (Fig. 4) to clear the adjacent pin 20—at which time each spring 26, acting through the tooth of its latch-member 25, will initiate this clockwise swinging of its bar 9 sufficiently to permit of the parts being collapsed to the broken-line locations shown in Fig. 4, upon downward pressure being exerted against the breast-rail 12. The seat 16, it will be remembered, is flexibly suspended, and will be accommodated within base-ring 5. Fig. 4 shows in collapsed condition merely one of the struts, but it will of course be understood that when collapsed each of the struts will be so arranged that the free ends of bars 9 will as indicated in said Fig. 4, point 100 toward the center of the base-ring.

It will be seen that the device as collapsed is exceedingly compact and convenient of storage and handling; it has also been pointed out in what manner various 115 objects herein set forth and indicated, have been attained; and it will follow that I have provided an embodiment of this invention well calculated to attain all possible ends and aims thereof.

Inasmuch as many changes could be made in the above construction, and many apparently widely different embodiments of my invention could be made without departing from the scope thereof, it is intended that all matter contained in the above description or shown in the accompanying drawing shall be interpreted as 125 illustrative and not in a limiting sense.

It is also to be understood that the lan- 130

guage used in the following claims is intended to cover all the generic and specific features of the invention herein described and all statements of the scope of the invention which, as a matter of language, might be said to fall therebetween.

I claim:

1. A device of the class described, in combination, a base ring, a breast rail and a plurality of pivoted rod connections between the base ring and the breast rail, means for maintaining the rods in alinement when extended and a spring actuated lever associated with each rod connection to lock the rods in their alined position, said lever also constituting a means for throwing the rods out of alinement when the alining means is disengaged.

2. In a device of the class described, in combination, a base ring, a breast rail, a seat connected to said breast rail, and a plurality of connections between said base ring and said breast rail, each of said connections including a plurality of relatively movable parts, means for alining said connections when extended, each of said relatively movable parts having associated therewith a spring actuated pivoted lever, said lever constituting a means for locking the connections in their alined position and also a means for throwing the connections out of alinement when the alining means is released.

3. In a device of the class described, in combination, a base ring, a breast rail, a seat connected to said breast rail, and a plurality of connections between said base ring and said breast rail, each of said connections including a plurality of relatively movable parts, a pin and an open slotted connection between the parts for

maintaining them in an alined position, and a spring actuated lever associated with one of the parts of a connection and coöperating with the opposite part to lock the said parts in their alined position, said spring actuated lever also constituting a means for throwing the parts out of alinement when the alining means is disengaged. 45

4. In a device of the class described, in combination, a base ring, a breast rail, a plurality of members each of which is pivotally suspended from said breast rail, a plurality of struts each including a plurality of spaced bars, each of said struts 55 being pivotally mounted at its lower end on said base ring, a slot and pin connection between each of said members and each of said struts, a plurality of alining means each of which is partially carried by one of 60 said members and partially carried by the associated strut all so arranged that each of said members may be alined relatively to its associated struts to dispose a portion of said member between the bars of said 65 associated strut thereby to permit said alining means to be predeterminedly set, a notch formed in the outer edge of each of said members, and a spring actuated pivoted latch lever associated with each strut and carrying a tooth adapted to engage the notch of the associated member when said 70 alining means is set, said lever also constituting a means for throwing the strut and its associated member out of alinement when 75 the alining means is disengaged.

In witness whereof I have hereunto signed my name in the presence of two witnesses.

JOSEPH GANNON.
